UNITED STATES PATENT OFFICE.

TAYLOR BURROWS, OF LONDON, ENGLAND, ASSIGNOR TO THE FLAX COMBING SYNDICATE, LIMITED, OF SAME PLACE.

MACHINE FOR COMBING VEGETABLE FIBERS.

SPECIFICATION forming part of Letters Patent No. 633,795, dated September 26, 1899.

Original application filed December 29, 1897, Serial No. 664,402. Divided and this application filed January 20, 1899. Serial No. 702,827. (No model.)

To all whom it may concern:

Be it known that I, TAYLOR BURROWS, engineer, a subject of the Queen of Great Britain, residing at 88 Upper Kennington Lane, 5 London, England, have invented certain new and useful improvements in or relating to circle combing-machines or the like primarily to adapt same for combing vegetable fibers, such as flax or china-grass, (for which I have 10 obtained the grant of Letters Patent in Great Britain, dated December 4, 1897, No. 28,680^a), of which the following is a specification.

This invention relates to circle combing-machines or the like, the same being a division of an earlier application filed by me December 29, 1897, and serially numbered 15 664,402, and primarily has for its object to adapt same for combing vegetable fibers, such as flax or china-grass; and it consists of improvements in or relating to dabbing the fiber 20 into the circular combs and in the method and means employed in this connection.

Figure 1 is a side view of a part of a combing-machine, showing my dabbing device. 25 Fig. 2 is a cross-section of the same on the line 8 8 of Fig. 1, and Fig. 3 is a horizontal cross-section of the same on the line 9 9 of Fig. 1.

Referring to the figures, a series of plates 30 or strips *h* of metal or other suitable material are arranged edgewise on a block *h'* and of any suitable width or widths, but always so as to be adapted to enter in the spaces between the respective circular rows of teeth *i* 35 in the main comb and in such wise that the said plates or strips *h* will not strike or touch such comb-teeth or pins *i* or in any wise injure same.

i' i' are the pins or combing-teeth on the 40 small circular combs, as shown in the drawings.

The plates *h h* pass through a sort of grid or fixed guiding device *j*, held just above the points of the circular combing-teeth or pins *i*. 45 Such guiding device *j* while permitting free vertical reciprocation of the strips or plates *h* will serve as guides to said plates and prevent lateral motion thereof, whereby it follows that such plates can enter only into the spaces 50 between the said rows of teeth *i* and similarly with respect to the pins *i'*. In addition

to this the ordinary "plows" or fixed inclined plates *k* on edge (which are inserted between the rings of teeth *i* of the main circular comb in order to lift out the ends of the 55 fibers in readiness to permit the feeding operation to take place) are mounted as usual or in any suitable manner, and then such inclined plates *k* are prolonged at *l* and descend and extend toward and under the dabbing- 60 plates *h*, or the strips or plates *l* may advantageously be separate from the plows *k*. The ends *l'* of said plates *l* extend quite under the dabbing device and are fixed and held rigidly between the respective revolving 65 circular rows of pins or teeth *i* of the main circular comb, so as to insure the said rows of pins or teeth *i* being maintained at their proper distances apart, and this definite position of the parallel rows of pins or teeth *i* 70 is thus insured and maintained and the said strips or plates *h* on the block or support *h'* being reciprocated vertically always in the same vertical plane—for instance, by the reciprocating plunger or connecting-rod *y*. Consequently it is thus insured that the said dabbing-plates *h* will always accurately fit or enter between the circular rows of teeth *i* without 75 touching the latter and enable rigid plates, such as *h*, to be used instead of bristles. 80

Having thus described my invention, what I claim, and desire to secure by Letters Patent of the United States, is—

1. In a circle-comb, the combination of a fixed guiding device provided with perforations and a dabbing device consisting of a series of dabbing-plates mounted on a block and means for reciprocating said dabbing device, substantially as described. 85

2. In a circle-comb, the combination of the frame of a machine provided with a comb, a fixed guiding device provided with slots, a reciprocating dabbing device consisting of a series of dabbing-plates carried by a block and acting-rod, guides for said rod and means 95 for reciprocating said acting-rod, substantially as described.

TAYLOR BURROWS.
